UNITED STATES PATENT OFFICE.

ADOLF HOLLAND, OF MAGDEBURG, GERMANY.

CENTRIFUGAL APPARATUS.

SPECIFICATION forming part of Letters Patent No. 716,711, dated December 23, 1902.

Application filed June 10, 1902. Serial No. 111,003. (No model.)

To all whom it may concern:

Be it known that I, ADOLF HOLLAND, a citizen of Germany, residing at Magdeburg, in the Kingdom of Prussia, Empire of Germany, have invented certain new and useful Improvements in Centrifugal Apparatus, of which the following is a specification.

This invention relates to a centrifugal apparatus, and relates particularly to improvements in collecting-plates for this class of devices as disclosed in Letters Patent No. 703,728, granted to me July 1, 1902.

The object of the same is to provide means whereby liquids of different density and quality can be readily separated and collected into separate chambers.

To this end the invention consists of a centrifugal apparatus comprising a base-plate divided into compartments, a collecting-plate 20 having a plurality of openings, a movable cover-plate having corresponding recesses adapted to register with said openings, and guiding-blades on said cover-plate for directing the flow of liquid to a predetermined compartment, as will be more fully described hereinafter, and finally pointed out in the claims.

In the accompanying drawings, Figures 1 and 2 are plan views, respectively, of the collecting-plate and cover-plate. Fig. 3 is a central vertical section of the base-plate of the centrifugal apparatus with the collecting-plate in position. Fig. 4 is a transverse section of the cover-plate. Figs. 5 and 6 are plan views, respectively, of modified forms of collecting-35 plate and cover-plate. Fig. 7 is a central vertical section of the lower portion of a modified form of apparatus. Fig. 8 is a transverse section of a cover-plate for the same. Fig. 9 is a central vertical section of my improved 40 centrifugal apparatus, and Fig. 10 is a plan view thereof partly broken away.

Similar letters of reference indicate corresponding parts.

Referring to the drawings, as shown in Figs. 45 2 and 9, the base-plate of the apparatus is divided into collecting compartments or chambers *a* and *b*, which are provided with discharge-openings *c* and *d*, respectively, the same being similar to the construction shown 50 in said before-mentioned Letters Patent. I

have provided the annular collecting-plate *e* with regularly-spaced openings *k*, that extend the width of the plate or approximately the entire width between the interior and exterior edges thereof, said openings *k* being 55 separated by the portions *m*, approximately the same length as the openings *k*. Upon the collecting-plate *e* is movably supported a cover-plate *f*, annular in shape and having regularly-spaced radial recesses *k'*, extending into the body of the same from its inner periphery. These recesses *k'* form the projecting or covering portions *n*, which are slightly larger than the portions *m* of the collecting-plate *e*, while the recesses *k'* are somewhat smaller than the openings *k*, so that the covering portions *n* will completely close the openings when properly adjusted. Downwardly-diverging blades *l* are provided upon the upper surface of the covering portions *n*, 70 that serve to turn the course of the liquid gathering on the cover-plate into the openings *k* of the collecting-plate, when said plate and cover-plate are so adjusted as to have the recesses of the latter in register with the 75 openings of the former for collecting the liquid into the chamber *a*. In order to direct the flow of liquid into chamber *b*, the openings of the collecting-plate *e* are closed by moving the cover-plate axially, so that the 80 covering portions thereof will cover the openings, and then the liquid will flow down the collecting-plate and cover-plate and run off between the blades *l* into the chamber *b*.

The modification shown in Figs. 5 to 8 is a 85 construction of the apparatus which is utilized when it is desired to separate the liquid into more than two qualities. The base-plate is provided with collecting compartments *a*, *q*, and *b*, formed by upright annular flanges 90 *o* *o*, adjacent to the circumferential flange of the base-plate, said compartments having, respectively, the discharge-outlets *c*, *r*, and *d*. The collecting-plate *e* in this construction is provided with openings *k*, that are arranged 95 in regularly-spaced pairs, the same being staggered in two concentric circles. These openings are sufficiently wide to extend transversely across the annular chambers—that is, one row arranged over each chamber. Be- 100

tween the pairs of openings *k* are the closed portions *m*, approximately the same length as an opening *k*.

The cover-plate *f* instead of having the recesses and the covering portions *n* of the same length, as shown in Figs. 1 and 3, the recesses *k* are as wide as the length of one of the openings *k* in the collecting-plate, and the intermediate portions *n* of the cover-plate 10 are each equal to a portion *m* and an adjacent opening *k*, as shown in Fig. 5 and 7, so that the covering portion *n* will always cover one or the other row of openings *k*. This form of cover-plate permits of only one row 15 of openings of the collecting-plate to be open at one time, so that the liquid can be directed in either of the annular chambers, or the complete closing of all the openings simultaneously, so as to cause the liquid to flow 20 over the cover and collecting plates and discharge into the central chamber *b*. The portions *n* are provided with blades *b*, that diverge from adjacent the outer periphery to points that lie in a line about medial of the inner 25 and outer peripheries, so that the liquid is directed into the chamber *a* or *q*, according to whether the upper or lower row of openings is uncovered.

Having thus described my invention, I 30 claim as new and desire to secure by Letters Patent—

1. In a centrifugal apparatus, the combination, with a base-plate having a plurality of compartments, of a collecting-plate provided 35 with openings communicating with said compartments, a cover-plate having recessed por-

tions to permit the covering and uncovering of said openings, and guiding-blades on said cover-plate, substantially as set forth.

2. In a centrifugal apparatus, the combination, with a base-plate having a plurality of separate chambers, of a collecting-plate provided with a plurality of evenly-spaced openings, a cover-plate provided with evenly-spaced recessed portions, said recessed portions being adapted to open or close said openings for directing the flow of liquid separately into one of said chambers, substantially as set forth. 40 45

3. In a centrifugal apparatus, the combination, with a base-plate having a plurality of separate annular chambers and a central chamber, of a collecting-plate supported above said annular chambers and provided with annular rows of openings evenly spaced apart 50 in staggered groups, a cover-plate supported on said collecting-plate having regularly-spaced recesses corresponding in width to the length of said openings and having intermediate covering portions between said recesses 55 for covering either one of the rows of openings, and guiding-blades on said intermediate covering portions for directing the flow of liquid separately into any one of said chambers, substantially as set forth. 60 65

In testimony that I claim the foregoing as my invention I have signed my name in presence of two subscribing witnesses.

ADOLF HOLLAND.
